UNITED STATES PATENT OFFICE

12,000,921 of feed to side of sole

MARKING MACHINE

Frank C. Cheice, Leicester, England, assignor to Boring Head and Body Company, United Shoe Machinery Corporation, Paterson, New Jersey, a corporation of New Jersey

Application October 26, 1932, Serial No. 639,861
In Great Britain November 4, 1931

12. Claims.

This invention relates to machines for use in the manufacture of boots and shoes and is illustrated herein as embodied in a machine particularly adapted for marking or treating soles to indicate to an operator the position along the sole where an operation thereon should begin or end.

When preparing soles for use in the manufacture of boots and shoes, particularly outer soles, it is sometimes desirable to reduce the thickness of the margin of the sole along the shank to improve the appearance of the finished shoe. Such a reduction of the margin of the sole usually extends between the ball line and the heel breast line at the shank of the sole and it is important to the appearance of the finished shoe that the reduction should not extend beyond these points.

The shank reducing operation is usually performed on a machine by presenting first one side margin of the sole and then the other to a pair of feed rolls which grip the margin of the sole and feed the sole past a beveling cutter fixed in the machine. When a machine of this type is used for this purpose the operator has to determine the positions along the sole margin where the beveling begins and ends, with the result that these positions may not be accurately located in some soles and the appearance of the finished shoe may be spoiled.

One object of this invention is to provide an improved machine for operating upon shoe soles the use of which will overcome these difficulties.

In accordance with this object a feature of the invention resides in a machine for operating upon soles provided with means for positioning the sole longitudinally and means engaging the sole adjacent to the toe end at only one side and adjacent to the heel end at only the other side for positioning the sole with its longitudinal median line at an angle to an operating tool, thus enabling an operator to position a sole quickly and accurately by engagement of the sole with a minimum number of positioning means. As illustrated, the means for positioning the sole with its longitudinal median line at the desired angle to the marking tool comprises two pairs of equally and oppositely adjustable positioning members, illustrated as abutment pins, and arranged to permit selected groups of pins from the two pairs to be used to position alternatively right and left soles relatively to the marking means at the will of the operator.

The invention will now be more particularly described by reference to the accompanying drawings and thereafter pointed out in the claims.

In the drawings.

Fig. 1 is a view in side elevation, partly in section, of a preferred form of a machine embodying the present invention;

Fig. 2 is a plan view of the machine;

Fig. 3 is a plan view of the work supporting table and work positioning devices;

Fig. 4 is a view in side elevation of some of the parts of the machine shown in Figs. 1 and 2, but showing the parts in different relative positions; and

Fig. 5 is a detailed plan view of a gage for positioning the heel end of a shoe in the machine.

The illustrated machine comprises a frame 2 which is adapted to be secured to a work bench or other suitable support. At its rear end the frame is provided with bearings for a horizontal shaft 4 which extends across the machine. The drive shaft 4 has rotatably mounted in its right-hand end a pulley 6 which may be connected by a single revolution clutch, part of which is shown at 8, to the drive shaft 4. The drive shaft 4 has formed on it between its bearings an eccentric 10 which is surrounded by the large end of an eccentric link 12. The forward end of the link 12 is connected by a pin 14 extending across the machine to the lower end of a marking tool lever 16 pivoted to the frame 2. The marking tool lever 16 is formed as a pair of arms joined at their upper ends by a cross-piece 18. The arms are fixed between the cross-piece and the lower end of the lever 16 to short shafts 20 which are rotatably mounted in bearings at opposite sides of the frame 2. This construction of the marking tool lever permits a work positioning device, hereinafter to be described, to project between the arms.

The crosspiece 18 of the marking tool lever 16 has mounted on it a marking tool 22. The marking tool 22 is in the form of a flat plate having one edge formed to mark a straight line across the sole. The plate 22 is mounted in a recess in the crosspiece 18 and has formed in it a pair of parallel slots. Two screws 26, 28 fixed in the crosspiece 18 and extending through the slots guide the tool 22 and limit its movement out of the recess under the influence of two springs, one of which is shown at 28 in Fig. 11. These springs 28 are mounted in the crosspiece 18 and engage opposite ends of the marking tool 22. The tension of the springs 28, 28 may be adjusted by screws 126, 128. If the margins of a sole to be marked in the machine vary in thickness the springs 28 allow the marking tool 22 to accommodate itself to the thicknesses of the sole and also allow the marking tool to accommodate itself to soles which, al-

though they are of uniform thickness, may be thicker or thinner than other soles. To insure that the sole is marked clearly at its edges the work marking edge of the tool 22 is slightly bowed so that the pressure of the tool is greater at its ends than at its midportion.

When the drive shaft 4 is rotated the marking tool 22 is swung down about the axis of the pivots 20 of the marking tool lever 16 toward a horizontal work supporting table 30 fixed to the front of the frame 2. The edge of the plate 22 which forms the marking tool is brought into contact with a sole placed on the work supporting table 30 to mark a straight line across the sole at the ball line from edge to edge thereof and thus indicated where the operation of shank reducing should begin or end.

Rotatably mounted in the frame 2 below the table 30 is a horizontal shaft 32 which extends across the machine and is prevented from moving axially by a collar 34 at one end and a hand wheel 36 at the other end. The collar 34 and the hand wheel 36 engage the side faces of the frame 2 and the shaft may be rotated by turning the hand wheel 36. The shaft 32 is provided with right- and left-hand screw-threaded portions, shown best in Fig. 3, which are threaded through blocks 38, 38 which are guided in a guideway formed in the frame. Rigidly secured to each of the blocks 38 is a bar 40 which extends lengthwise of the machine rearwardly beyond the back edge of the table 30. Each bar has fixed in it a gage or gages to contact with the lateral edge of a sole and here shown as two pins 42 which extend up beyond the top surface of the table 30, the rear pins extending at the back of the table and the front pins extending through slots 44, 44 formed in the table. By means of the right- and left-hand threaded portions of the shaft 32 the bars 40 and their pins 42 may be adjusted toward and from each other to position laterally a sole to be marked as later described. Since, as noted above, the machine is arranged so that either right or left soles may be presented alternatively, the spacing of the gages 42, as measured in a direction parallel to the abutment plate 50 between lines from said gages normal to the plane of the abutment, will be greater than the width of a sole. In other words, the distance between projections from said gages upon the abutment 50 or an extension thereof, if outside the abutment, will be greater than the width of a sole thereby bringing the longitudinal axis of a sole, positioned as illustrated in Fig. 3, at an angle with the abutment which is less than a right angle. The word "projection" is here used in the mathematical sense to mean a line let fall from a particular point, said line being normal to the surface or line upon which it is projected. This will also bring the axis at an acute angle to the elongated marking tool 22.

A third bar 46 is arranged to be moved forwardly and rearwardly of the machine. The bar 46 is guided in a groove formed in the under side of the work table 30 and is supported on the face of the frame 2 to which the table is fixed. The bar 46 may be locked in position by a hand screw 48 (Fig. 1) extending upwardly through a boss formed at the front of the machine frame and engaging the under side of the bar 46 to clamp it in position. Fixed to the rear end of the bar 46 is an end gage plate 50 which extends upwardly above the upper face of the work table 30 and across the machine. The gage plate 50, in the form of a straight abutment, is used to position the

toe end of the sole which is to be marked at the ball line. A gage block 52 (Fig. 5) may be placed on the gage plate 50. This block has in its front face a V-shaped recess 54 in which the heel end of the sole is placed. The gage block 52 is held in position on the gage plate 50 by a pin 56 in the gage block which enters a vertical recess 58 (Fig. 3) in the top of the plate 50 which positions the block centrally of the work table, the block 52 resting on top of the bar 46.

The work table has a mark 60 (Fig. 3) extending across its upper face which coincides with the position of the marking tool 22 when the tool is swung nearly into contact with the upper surface of the table. The right front pin 42 is cut away for part of its length on the outer side so that a flat surface 62 thereon (Figs. 2 and 3) serves as an indicator and cooperates with a row of index marks 64 on the upper face of the work support 30 which indicate the distance apart of the two sets of pins 42 on the bars 40. The bar 46 has a row of marks on its upper face which by their relation to an edge 65 of a recess in the table indicate the position of the gage 50 relatively to the mark 60 on the table.

By means of the mark 60 the operator is enabled to place by eye a sole on the work table 30 in correct position to be marked at the ball line by the marking tool 22 when the machine is put into operation. Then the gage plate 50 and two of the lateral gage pins 42 may be moved into engagement with the sole contacting therewith at three places, so that subsequent soles of the same size and shape to be marked may be quickly positioned upon the work table by being placed against the gage plate and the pins.

When the soles are to be marked at the ball line the gage 52 is removed and the toe end of the sole is positioned by the gage plate 50 to determine the distance of the mark from the end of the sole. The angle of the mark in relation to the longitudinal median line of the sole is determined by the pins 42. Considering a left sole, for example, this lateral position is determined by moving the pins 42 until the rear pin 42 of the right-hand pair engages the sole at one side near the toe, with the forward pin 42 of the left-hand pair engaging the other edge or side of the sole adjacent to the heel end, as shown in Fig. 3. The pins 42 make, as shown, vertical line contact with the sides of the sole and, hence, contact with limited portions thereof. Right soles of the same size and shape may then be readily positioned for marking without altering the position of the pins by positioning them against the end gage 50 and appropriate pins. In other words, a left sole is positioned by the right-hand rear pin and the left-hand front pin and the right sole is positioned by a left-hand rear pin and a right-hand front pin.

When marking the sole at the breast line the gage block 52 is placed on the gage plate 50 and the pins 42 are not used to position the sole. The gage block 52 is positioned an appropriate distance behind the mark 60 on the work support in accordance with the size of the sole and the operator merely presents the heel end of the sole to the V-shaped recess 54 in the block 52 and positions the sole laterally.

Fixed on the upper face of the work support 30 at each side thereof are two brackets 66, 66. Extending across the front of the bracket 66 is a rectangular piece of safety glass 68 beneath the lower edge of which the soles are pushed on to the work support. These brackets 66 and safety glass

- 63 form a guard to prevent the operator's hands from being injured by the marking tool 22 and the glass 63 allows the operator to see that the sole is properly positioned against the gages.
- 5 The marking tool 22 is supplied with ink during each cycle of operations of the machine. The ink is carried by a felt-covered roll 10 extending horizontally across the machine and is rotatably mounted in the lower ends of a pair of arms 12, 10 of a swinging lever 14 which is pivoted on pins 16, 16 fixed to the upper rearward ends of the bracket 66. A rod 18 extends between the upper ends of the bracket 66 to brace the brackets and prevent undesired lateral movement of the upper 15 ends of the brackets. The arms 12 of the swinging lever 14 are connected by rearwardly and downwardly extending links 80, 80 to the marking tool lever 16 and the arrangement is such that when the machine is in its stopped position the marking edge of the marking tool 22 is approximately $\frac{1}{8}$ of an inch away from the periphery of the inking roll 10 and when the machine is put into operation the marking tool 22 first moves away from the work table to the limit of its 20 marking edge of the marking tool 22 is approximately $\frac{1}{8}$ of an inch away from the periphery of the inking roll 10 and when the machine is put into operation the marking tool 22 first moves away from the work table to the limit of its movement in this direction and through the links 80 draws the inking roll 10 into momentary contact with the marking edge of the marking tool 22, as shown in full lines in Fig. 4. Then, as the marking tool 22 is swung down toward the 25 work support, the inking roll 10 is swung by the links 80 away from the edge of the marking tool 22. Just before the roll comes into contact with the marking tool 22, as indicated in full lines in Fig. 4, the end of a spring blade 82 fixed to one 30 of the links 80 engages a ratchet wheel 84 on the inking roll 10 and during the first part of the downward or clockwise movement of the marking-tool lever 16 toward the work rotates the inking roll 10 so that a fresh portion of the inking roll 35 is presented to the marking edge of the tool 22 when the machine is operated again. The lower rearward ends of the links 80 connecting the marking tool lever 16 and the inking roll lever 14 are mounted upon eccentric portions 86 of a rod 88 fixed in the marking tool lever 16 so that by rotating the rod 88 the relationship of the inking roll 10 and the tool 22 may be adjusted when these are brought together as above 40 described.
- 50 The inking roll 10 is mounted in the arms 12, 12 so that it can be readily removed for inking, cleaning, or any other purpose, and replaced. A spindle 90 to which the roll 10 and the ratchet wheel 84 are fixed has slidably mounted axially on each 55 end a knurled collar 92 which has formed on it a boss 94 which enters a recess 96 (Fig. 1) formed on the outer face of each of the arms, there being an open-ended slot 98 on the end of each arm to receive the spindle.
- 60 Having described my invention, what I claim as new and desire to secure by Letters Patent of the United States is:
1. A machine for operating upon soles having, in combination, a work support, an operating tool arranged for movement toward and away from said work support, sole-end-engaging means for positioning a sole longitudinally, and means engaging the sole adjacent to the toe end only at one side and adjacent to the heel end only at the other side for positioning the sole with its longitudinal median line at an angle to the operating tool.
  2. In a machine for operating upon soles having, in combination, a work support, an elongated operating tool, means on said support for posi-
- tioning a sole longitudinally, and means engaging the sole adjacent to the toe end only at one side and adjacent to the heel end only at the other side for positioning the sole with its longitudinal median line at an angle to the operating tool. 5
3. A machine for operating upon soles having, in combination, a work support, an elongated operating tool, sole-end-engaging means and support for positioning a sole longitudinally, and means engaging the sole adjacent to the toe end only at one side and adjacent to the heel end only at the other side for positioning the sole with its longitudinal median line at an angle to the operating tool. 10
4. A machine for marking soles having, in combination, a work support, a marking tool arranged for movement toward and away from said work support, sole-end-engaging means on said support for positioning a sole longitudinally, and means engaging the sole adjacent to the toe end only at one side and adjacent to the heel end only at the other side for positioning the sole with its longitudinal median line at an angle to the operating tool. 15
5. A machine for marking soles having, in combination, a work support, a marking tool arranged for movement toward and away from said work support, sole-end-engaging means on said support for positioning a sole longitudinally, and means engaging the sole adjacent to the toe end only at one side and adjacent to the heel end only at the other side for positioning the sole with its longitudinal median line at an angle to the operating tool. 20
6. A machine for marking soles having, in combination, a work support, a marking tool arranged for movement toward and away from said work support, sole-end-engaging means on said support for positioning a sole longitudinally, and means engaging the sole adjacent to the toe end only at one side and adjacent to the heel end only at the other side for positioning the sole with its longitudinal median line at an angle to the operating tool. 25
7. A machine for marking soles having, in combination, a work support, a marking tool arranged for movement toward and away from said work support, sole-end-engaging means on said support for positioning a sole longitudinally, and means engaging the sole adjacent to the toe end only at one side and adjacent to the heel end only at the other side for positioning the sole with its longitudinal median line at an angle to the operating tool. 30
8. A machine for marking soles having, in combination, a work support, a marking tool arranged for movement toward and away from said work support, sole-end-engaging means on said support for positioning a sole longitudinally, and means engaging the sole adjacent to the toe end only at one side and adjacent to the heel end only at the other side for positioning the sole with its longitudinal median line at an angle to the operating tool. 35
9. A machine for operating upon soles having, in combination, a work support, an operating tool arranged for movement toward and away from said work support, sole-end-engaging means on said support for positioning a sole longitudinally, and means spaced apart a distance, measured in a direction parallel to said plate, which is greater than the width of the sole for engaging the sole adjacent to the toe end at one side and adjacent to the heel end at the other side for positioning the sole with its longitudinal median line at an angle to the operating tool. 40
10. A machine for operating upon soles having, in combination, a work support, an operating tool arranged for movement toward and away from said work support, sole-end-engaging means on said support for positioning a sole longitudinally, and means spaced apart a distance, measured in a direction parallel to said plate, which is greater than the width of the sole for engaging the sole adjacent to the toe end at one side and adjacent to the heel end at the other side for positioning the sole with its longitudinal median line at an angle to the operating tool. 45
11. A machine for marking soles having, in combination, a work support, a marking tool arranged for movement toward and away from said work support, sole-end-engaging means on said support for positioning a sole longitudinally, and means comprising a plurality of positioning members arranged to be equally and oppositely adjusted to permit different pairs of the members to be used to position right and left soles at the will of the operator. 50
12. A machine for marking soles having, in combination, a work support, a marking tool arranged for movement toward and away from said work support, sole-end-engaging means on said support for positioning a sole longitudinally, and means comprising a plurality of positioning members arranged to be equally and oppositely adjusted to permit different pairs of the members to be used to position right and left soles at the will of the operator. 55
13. A machine for marking soles having, in combination, a work support, a marking tool arranged for movement toward and away from said work support, sole-end-engaging means on said support for positioning a sole longitudinally, and means spaced apart a distance greater than the width of the sole for engaging the sole adjacent to the toe end only at one side and adjacent to the heel end only at the other side for determining the angular relation to the marking tool of either a right or a left sole. 60
14. A machine for marking soles having, in combination, a work support, a marking tool arranged for movement toward and away from said work support, sole-end-engaging means on said support for positioning a sole longitudinally, and means spaced apart a distance greater than the width of the sole for engaging the sole adjacent to the toe end only at one side and adjacent to the heel end only at the other side for determining the angular relation to the marking tool of either a right or a left sole. 65
15. A machine for marking soles having, in combination, a work support, a marking tool arranged for movement toward and away from said work support, sole-end-engaging means on said support for positioning a sole longitudinally, and means spaced apart a distance greater than the width of the sole for engaging the sole adjacent to the toe end only at one side and adjacent to the heel end only at the other side for determining the angular relation to the marking tool of either a right or a left sole. 70
16. A machine for marking soles having, in combination, a work support, a marking tool arranged for movement toward and away from said work support, sole-end-engaging means on said support for positioning a sole longitudinally, and means spaced apart a distance greater than the width of the sole for engaging the sole adjacent to the toe end only at one side and adjacent to the heel end only at the other side for determining the angular relation to the marking tool of either a right or a left sole. 75

side, to position the sole with its longitudinal median line at an angle to the marking tool, said last-mentioned means comprising two pairs of equally and oppositely adjustable pins arranged 5 to permit different pins of each pair to be used to position right and left soles at the will of the operator.

9. A machine for marking soles having, in combination, a work support, a marking tool arranged 10 for movement toward and away from said work support, an adjustable slide on the work support for engaging the toe end of the sole to position the sole longitudinally relatively to the marking tool, and a pair of pins arranged to engage the sole adjacent to the toe end on one side and adjacent to the heel end on the other side to position the sole laterally with its longitudinal median line at an angle to said marking tool, said pins being arranged to be oppositely adjusted.

10. A machine for marking soles having, in combination, a work support, a marking tool arranged for movement toward and away from said work support, an adjustable slide on the work support for engaging the toe end of a sole 25 to position the sole longitudinally relatively to the marking tool, a pair of bars, pins on said bars extending above the work support, one pin on one bar being arranged to engage the sole adjacent to the toe end on one side and a pin on the other bar arranged to engage the other side of the sole adjacent to the heel end to position the sole laterally, and means for equally and oppositely adjusting said bars to permit the pins to be moved toward and away from each other to position the sole of different shapes and styles relatively to the marking tool.

11. A machine for operating upon soles near

the ball line having, in combination, a work support, an operating tool movable to engage a sole positioned thereon, a straight abutment engaging the end of a sole to position it longitudinally, and means for determining the angular position 5 of the sole with respect to the work support comprising a gage for making contact with a limited portion of the side of the sole near one end and another gage for making contact with a limited portion of the other side of the sole near the other end, the spacing between said members, as measured between lines from said gages normal to the plane of the abutment, being greater than the width of a sole whereby the longitudinal axis 10 of a sole positioned by the gages is not normal to the abutment.

12. A machine for operating upon soles near the ball line having, in combination, a work support, an operating tool movable toward and away from the work support to engage a sole positioned 20 thereon, a straight abutment engaging the end of a sole to position it longitudinally, and means for determining the angular position of the sole with respect to the work support comprising adjustable gages relatively fixed with respect to the work support and positioned to engage opposite sides of the sole near opposite ends thereof whereby the position of a sole on the work support is determined by the contact furnished at three 25 places on the sole by the abutment and the gages, the distance between the projections of said gages upon said abutment or an extension thereof being greater than the width of the sole whereby the longitudinal axis of the sole positioned by said three-point contact forms an angle less than a 30 right angle with the abutment.

FRANK COLEMAN CHOICE.
